WINDOW OPENING AND CLOSING
MECHANISM

Lawrence O. Burress, Moline, Ill.

Application September 12, 1951, Serial No. 246,245

2 Claims. (Cl. 268—108)

1

The present invention relates generally to window control mechanism and particularly to mechanism for controlling long hinged windows of the type commonly installed in foundries and other commercial buildings. Some windows of this class are sixty to eighty feet long, comprising a single frame hinged along the upper edge for swinging outwardly to open position.

Heretofore, the operating mechanism for swinging such windows has comprised a shaft extending along the window sill having a number of spaced crank arms extending radially from the shaft connected by links to the window sash. Inasmuch as the shaft turns less than one-half revolution to open the heavy window, it is evident that substantial torsional stress is set up in the shaft, resulting in an appreciable amount of "wind-up" in a long shaft. This angular difference in the positions of the crank arms imposes twisting strains in the window sash which sometimes causes breakage of the window glass.

The principal object of this invention, therefore, relates to the provision of a window control mechanism which applies a uniformly distributed force against the entire length of window sash. In the accomplishment of this object, an operating shaft is employed which has axially spaced portions threaded in relatively opposite directions with cooperatively threaded nuts movable along the shaft in opposite directions relative to each other. Arms connect the nuts with the sash and inasmuch as these arms are disposed in opposed relation to each other, the force applied to the sash is well distributed and side thrusts are balanced against each other, as will be apparent to those skilled in the art after a consideration of the following description, in which reference is had to the drawings appended hereto, in which

Figure 1 is a fragmentary perspective view of a window embodying the principles of this invention, the window being illustrated in open position;

Figure 2 is an enlarged sectional elevational view taken along a line 2—2 in Figure 1;

Figure 3 is a sectional elevational view of the control mechanism taken along a line 3—3 in Figure 4 but drawn to an enlarged scale;

Figure 4 is a top plan view of the control mechanism showing the window in closed position but showing in broken lines the position of the arms when the window is open;

Figure 5 is a sectional elevational view taken along a line 5—5 in Figure 4, drawn to an enlarged scale; and

2

Figure 6 is a perspective view, drawn to a still larger scale, of one of the ball and socket joints.

Referring now to the drawings, the window opening 9 in the building wall 10 is defined by a steel frame including upper and lower channel members 11, 12 and vertical channel members 13. The lower channel 12 serves as the window sill. Only one end of the window is shown, for the window may extend as far as eighty feet or more along the wall. The window 15 comprises a metal sash 16 of suitable conventional construction including a top rail 17, a bottom rail 18 and a number of laterally spaced generally vertical connecting members 19 for completing a rectangular sash frame and supporting the glass panes 20 in any suitable manner known to those skilled in the art. The upper rail 17 is shown as of extruded aluminum construction with a hinge portion 21 extending along the upper edge thereof and received within the socket 22 of a cooperative hinge member 23 which has a vertical flange 24 supported on the top frame channel member 11 by bolts 25. The lower rail 18 is provided with a flange 26 which bears against the front of the sill 12 in closed position.

Thus, the window is suspended by the interlocking hinge parts 21, 23 along its upper edge and is swingable toward and away from the sill 12. The window is swung between open and closed positions by means of control mechanism now to be described.

A horizontally disposed shaft 30 is mounted in spaced bearings 31, 32, 33, which are supported on brackets 34, 35, 36, respectively, attached to the sill channel 12. The shaft 30 is rotatable in said bearings about its major axis, the axis being parallel to the axis of swinging movement of the window on its hinge and also parallel to the sill.

The portion 37 of the shaft 30 between the first two bearings 31, 32 is threaded in one direction, say with a right-hand thread, and the next portion 38 of the shaft between the two bearings 32, 33 is threaded in the opposite direction, say with a left-hand thread. A pair of nuts 39, 40, having right- and left-hand threads, respectively, are mounted on the threaded portions 37, 38 of the shaft and are provided with radially extending ears or lugs 41, 42, formed integrally therewith. Actuating arms 43, 44 are pivotally connected at one end by pins 45, 46 to the lugs 41, 42 on the nuts 39, 40, respectively, and are swingable angularly relative to the shaft 30.

The opposite ends of the arms 43, 44 are flexibly

connected to the lower rail 18 of the window by means of universal joints 45 of novel construction. Referring more particularly to Figure 6, each of the universal joints 45 comprises a ball member 50 movable within a socket member 51. The ball 50 is carried on a neck 52 which is mounted on a bifurcated support comprising a pair of ears 54. The socket member 51 is formed integrally with a lug 55. The ears 54 are spaced to receive the outer end of the actuating arm 43 therebetween, and is suitably fixed thereto by a bolt or rivet 57 which extends through aligned apertures 58 in the ears and in the arm. The socket member 51 is attached to the window rail 18 by a bolt 59 which extends through aligned apertures 60 in the lug 55 and rail 18.

The universal joint 45 is a single unitary aluminum casting in two inseparable parts. The casting is made by first casting the ball member 50 in a conventional manner, then coating the ball 50 with a graphite lubricant and placing it in a mold, after which the socket member 51 is cast around it. The graphite prevents the adherence of the ball and socket and the joint is inseparable but rustproof.

In the closed position of the window the two nuts 39, 40 are positioned at opposite sides of the center bearing 32 and adjacent thereto, while the universal joints 45 are secured to the sash rail 18 spaced in relatively opposite directions from the bearing 32. The two actuating arms 43, 44 thus extend across the sill 12 in relatively opposite directions at acute angles to the shaft 30 when the window is closed. Rotation of the shaft in one direction shifts the nuts 39, 40 in relatively opposite directions away from the bearing 32 toward the other two bearings 31, 33, respectively, thus shifting the inner ends of the arms therewith toward positions (shown in broken lines) in which the arms are substantially perpendicular to the shaft. This urges the outer ends of the arms, together with the joints 45 and the window rail 18, outwardly to open the window.

It is evident, therefore, that during rotation of the shaft 30 axial forces in the shaft oppose each other and there is substantially no tendency to urge the shaft axially in either direction. Similarly, the forces transmitted to the window through the arms are balanced and do not tend to twist the sash but rather to urge the latter outwardly and to stress the rail 18 in tension between the joints 45. Inasmuch as the shaft is rotated a large number of revolutions between closed and open positions of the window, the torsional stress in the shaft is much lower than in shafts which open the window in less than one-half revolution; therefore, there is no perceptible "wind-up" in a shaft of eighty feet in length, thus eliminating any breakage of glass due to this cause.

The window is closed by rotating the shaft in the opposite direction to shift the inner ends of the arms toward the center bearing 32.

The distance between the bearings 31, 32 can be in the order of three or four feet, or a total of six to eight feet across the portion of the window shown in Figure 4. Other pairs of actuating arms are arranged in spaced relation over the remainder of a long window, although the shaft 30 extends across the entire length of the window. The shaft 30 can, however, be made up of a number of lengths of, say, eight feet in each length, joined together by tongue and groove joints, as indicated at 65 within the bearing 33.

The shaft 30 can be rotated by any suitable

means, either manually or power driven. Preferably it is driven by an electric motor 66 mounted on brackets 67 which are fixed to the sill channel 12. The motor is preferably of the type having a built-in reduction gearing, indicated by reference numeral 68 by which the motor shaft 69 drives the output shaft 70 at reduced speed. The output shaft 70 is coupled to the drive shaft 30 by a tongue and groove joint in the bearing 31 as indicated at 71.

A pair of limit switches 72, 73 are mounted on the brackets 34, 35, respectively, and are positioned to be engaged by the nut 39 at opposite ends of its travel to stop the motor at each end of the range of travel.

Although one embodiment of this invention has been herein shown and described, other variations and embodiments of the invention will be apparent to those skilled in the art. I do not intend to limit my invention to the particular details shown and described except as set forth in the claims which follow.

I claim:

1. In combination, a window frame, a multi-paned window hingedly mounted along its upper edge in said frame, the lower portion of said frame including a sill, said window being swingable outwardly of said frame toward and away from said sill, a continuous shaft disposed alongside said sill substantially parallel thereto and coextensive therewith, a plurality of pairs of right and left hand threaded portions on said shaft, said pairs of threaded portions being spaced lengthwise of the entire shaft, bearings for rotatably supporting said shaft disposed at the opposite ends of each pair of threaded portions and a gearing between each of said right and left hand threaded portions, said bearings being mounted on brackets affixed to said sill, threaded nuts engaging said threaded shaft portions, respectively, and movable toward and away from each other during rotation of said shaft in one direction or the other, respectively, actuating arms pivotally connected at one end with said nuts, respectively, and extending across said sill, universal joint means connecting the other ends of said arms with said window adjacent the lower edge thereof, said arms extending from said nuts at acute angles to said shaft in relatively opposite directions when said window is closed, and means for rotating said shaft to shift said nuts therealong in relatively opposite directions to urge said arms outwardly toward an open position in which said arms are generally perpendicular to said shaft, thus exerting a window opening force which is distributed over the entire length of the window.

2. The combination as claimed in claim 1 wherein said means for rotating said shaft comprises an electric motor means operatively connected to said shaft to rotate the same and shift said nuts therealong in relatively opposite directions to urge said arms outwardly toward an open position in which said arms are generally perpendicular to said shaft, and a pair of electric limit switches mounted at the extreme ends of one of said threaded shaft portions, one switch being adapted to be contacted by one of said travelling threaded nuts when said window is fully opened and the other switch being adapted to be connected by said same travelling nut when said window is fully closed whereby the operation of said electric motor means is stopped.
